UNITED STATES PATENT OFFICE.

LOUIS E. SADLER, OF ATTLEBORO, MASSACHUSETTS, ASSIGNOR TO THE F. H. SADLER COMPANY, OF ATTLEBORO, MASSACHUSETTS.

FINGER RING.

Application filed October 6, 1924. Serial No. 741,851.

To all whom it may concern:

Be it known that I, LOUIS E. SADLER, a citizen of the United States, residing at Attleboro, in the county of Bristol and 5 State of Massachusetts, have invented new and useful Improvements in Finger Rings, of which the following is a specification.

This invention relates to certain new and useful improvements in finger rings and the 10 primary object thereof is to provide a ring the body of which is formed of an integral member connected to form the bezel by means which also function to hold or assist in holding the stone or gem in position.

15 A further object of the invention is to provide a ring structure which can be economically produced and wherein the parts may be easily and quickly assembled.

20 A still further object of the invention is to provide a ring structure wherein the aforesaid holding means do not detract from the appearance of the ring and which enable same to possess the same general conventional effect or appearance common to 25 finger rings as customarily produced.

In the drawings:

Figure 1 is a side elevation of a ring constructed in accordance with the present invention.

30 Figure 2 is an end elevation;

Figure 3 is a section on line 3—3 of Figure 1;

Figure 4 is a plan view of the blank;

35 Figure 5 is a similar view of one of the connections and

Figure 6 is a side elevation showing a modified form of connector between the adjacent ends of one side of the bezel forming parts of the main blank.

40 In proceeding in accordance with the present invention a blank is employed which consists of a central bar 1 forming the usual finger loop and end bars 2 centrally connected to the ends of the bar 1 by flared parts 3.

45 Each end of the bar 2 has an opening 4 thereon. The blank is bent into the shape shown in Figures 1-3 of the drawings and with the bars 2 forming the bezel, the bar ends abutting as shown in Figure 3.

50 The bar ends are secured together by means of connectors or clamps 5 which latter extend across the lines of abutment of the ends of the bars 2 and are provided

with integral fingers 6 that extend through the respective openings 4 at the adjacent ends of the bars 2 and are bent so as to lie clinched against the inner faces of the ends of the bars 2. The clamps 5 are provided with prongs 7 which latter may be 55 of any desired number, Figure 5 illustrating a pair of prongs, while Figure 6 illustrates but one prong. Likewise the bezel-forming bars or parts 2 may be provided with similar prongs 8, and 9. This Figure 65 1, illustrates three prongs on a side of the bezel, while Figure 6 illustrates a prong 9 on the ends of the parts 2. In this regard it should be understood however that the arrangement and number of the prongs 70 both as to the bezel and the clamps may vary as desired, and similarly the shape of the bezel may likewise vary as desired to suit the taste and to accommodate stones or gems of varying shapes. The clamps thus 75 function in a dual manner, namely they connect the ends of the bezel-forming members together, and also assist in securingment of the gem in the bezel by virtue of the prongs carried thereby.

Having thus described my invention, what I claim as new and desire to secure by Letters Patent is:

1. In a finger ring, a body composed of a finger loop having integral members at 85 its ends arranged to abut and conjointly form a bezel, the ends of said members having apertures and clamps having prongs arranged to bridge the lines of abutment 90 of the members and having fingers extending through the apertures and clinched to the members in engagement with the inner faces thereof.

2. In a finger ring, a body composed of a finger loop having integral members at 95 its ends arranged to abut and conjointly form a bezel, the ends of said members having apertures and clamps bridging the lines of abutment of the members and having fingers extending through the apertures and 100 clinched to the members.

3. In a finger ring, a body composed of a finger loop having integral members at its ends arranged to abut and conjointly form a bezel, the ends of said members having apertures, and means extending through the apertures to connect the ends of the member together.

4. In a finger ring, a body composed of a finger loop having members at its ends arranged to conjointly form a bezel, and means to connect the adjacent ends of the
5 members together having gem engaging parts to assist in holding the gem in the bezel.

In testimony whereof I have signed my name to this specification in the presence of two subscribing witnesses.

LOUIS E. SADLER.

Witnesses:

AUGUSTA GRAY,
LOUISE BLANCHARD.
